(57) **CLAIM**

The ornamental design for a hematology test cassette with prefilled reagents, as shown and described.

DESCRIPTION

FIG. 1 is a perspective view of a hematology test cassette with prefilled reagents showing an embodiment of the new design, the cassette being translucent and having transparent diaphragms covering an upper surface and a bottom surface of the cassette, respectively, and with a label attached on an area of the upper surface;

FIG. 2 is a top plan view of the cassette shown in FIG. 1; FIG. 3 is a bottom plan view of the cassette shown in FIG. 1; FIG. 4 is a front elevational view of the cassette shown in FIG. 1;

FIG. 5 is a rear elevational view of the cassette shown in FIG. 1;

FIG. 6 is a left side elevational view of the cassette shown in FIG. 1;

FIG. 7 is a right side elevational view of the cassette shown in FIG. 1;

FIG. 8 is a perspective view of the hematology test cassette with prefilled reagents showing another embodiment of the new design, the cassette being non-translucent and having non-transparent diaphragms covering the upper surface and the bottom surface of the cassette, respectively, and with a label attached on an area of the upper surface;

FIG. 9 is a top plan view of the cassette shown in FIG. 8; FIG. 10 is a bottom plan view of the cassette shown in FIG. 8; FIG. 11 is a front elevational view of the cassette shown in FIG. 8;

FIG. 12 is a rear elevational view of the cassette shown in FIG. 8;

FIG. 13 is a left side elevational view of the cassette shown in FIG. 8; and,

FIG. 14 is a right side elevational view of the cassette shown in FIG. 8.

The broken lines are included for the purpose of illustrating portions of the hematology test cassette with prefilled reagents, and form no part of the claimed design.
